UNITED STATES PATENT OFFICE.

FREDERICK HOPKINS, OF BUFFALO, NEW YORK.

EXPRESSION-INDICATIONS FOR PERFORATED NOTE-SHEETS FOR PLAYER-PIANOS AND THE LIKE.

1,226,332.

Specification of Letters Patent. Patented May 15, 1917.

Application filed September 18, 1916. Serial No. 120,876.

To all whom it may concern:

Be it known that I, FREDERICK HOPKINS, a citizen of the United States, and a resident of Buffalo, in the county of Erie and State 5 of New York, have invented certain new and useful Improvements in Expression-Indications for Perforated Note-Sheets for Player-Pianos and the like, of which the following is a specification.

10 This invention relates to an improvement in the manner of indicating on note sheets or the like, as for instance the well known perforated note sheets for automatic or partially automatic musical instruments, the expression which the operator of such instruments is to observe in the performance of the musical compositions represented by such note sheets, together with any other directions or information appropriate or incidental to the performance of the music or 15 the operation of the sheets.

The expression indications on such note sheets have heretofore consisted principally of a dotted or solid line drawn or otherwise 20 superimposed upon the note sheet and traversing it throughout the perforated portion, and indicating dynamic degrees and changes, that is, the degrees and changes of degree of 25 loudness and softness to be observed in performance, by means of the position of such line on the sheet, together with directions as to tempo, dynamics and other details of 30 interpretation in the form of words, figures or symbols, stamped or otherwise superimposed 35 upon such sheet as nearly as practicable at the appropriate locations.

This system of expression indication by 40 means of superimposed lines and symbols, as heretofore employed, has several disadvantages. Such lines and symbols are usually superimposed upon the note sheets not as part of the operation of perforating in the 45 perforating machine, or simultaneously with such operation, but by a subsequent, separate operation or series of operations which add considerably to the cost of manufacture. Efforts to reduce the cost of expression marking result frequently in excessive simplification of line and symbols and in care- 50 less work. Few music rolls bear as many expression indications as are deemed necessary to manual performance, or even as many as would conduce to an intelligent interpretation of the music on the automatic or partially 55 automatic player, and such expression

marks as do appear on the note sheet are seldom in exactly the correct locations. The very application of inked, stamped or printed lines and symbols renders necessary a distinct application to the surface of each roll, 60 with resultant inaccuracies, and precludes or renders very difficult the simultaneous marking of a group of rolls, as for instance of a whole unseparated cutting of rolls as they pass through the perforating machine. It 65 has long been recognized as desirable that a system be devised by which the expression indications shall be added to the note sheets as part of the original single operation of perforating, and in as full and complete detail as may be wished, and with absolute and undeviating accuracy as to position and location on the note sheet.

The object of this invention is to provide expression indications for perforated note 70 sheets which shall be of absolute and undeviating accuracy as to their position and location on the note sheets, which shall also be as full, complete and comprehensive as may be desired and as the music may demand, 75 and which shall also be capable of being applied to the note sheets as part of the first operation of perforation on the perforating machine, involving no subsequent operation whatever.

In effecting the object of this invention it is to be considered that expression indications, whether of lines or symbols, perform no mechanical function in the operation of the playing machine, but are intended only 80 to be observed and followed by the eye of the performer, who translates them from their arbitrary symbolism into comprehensible directions, and carries out those directions in 85 performance. It is to be considered that the eye can as easily follow a dynamic or expression line formed by a succession of perforations as a line formed by a succession of printed dots or a solid drawn or printed line, and can as perfectly recognize a symbol 90 consisting of a perforation or a group of perforations as a letter, abbreviation or other symbol of the character now employed on note sheets when printed or stamped upon the sheet, especially if the perforations forming such 95 expression line or symbol are of a different size or shape from the perforations which perform a mechanical function in the operation of the playing machine.

It is to be considered also that while a 110

reason exists for employing upon sheet music the musical symbols presumably familiar to those who use such sheet music for manual performance, no such reason exists in the case of note sheets for partially 5 automatic musical instruments, because the users of such note sheets are not at first commonly familiar with musical symbols, and are obliged to learn arbitrarily the 10 meanings of such symbols as appear on the note sheets. It is therefore more rational to employ upon note sheets such symbols of interpretation as are most conveniently applied to the sheets and are most readily 15 recognized by the performer, no matter whether or not such symbols are those already accepted among musicians, or whether or not they are new symbols specially devised for the special conditions existing with 20 reference to note sheets and easily translatable into musical or other meanings.

It is to be considered also that the expression or dynamic line now generally used, which constantly changes its position on the 25 note sheet, and by its proximity to one side or the other of the sheet at any given point determines the dynamic value at that point, is less easy to follow than a line which preserves one single location on the note sheet, 30 and that if any one portion of the sheet is fixed upon as a location for the expression line, the eye quickly becomes accustomed to seek and follow that position.

It is to be considered also that in the 35 standard 88 note rolls, and indeed in all rolls, there is room somewhere in the width of the paper for extra perforations, especially if such perforations are not designed to track with perforations in a tracker bar. 40 And practically every perforating machine either is already equipped or can readily be equipped with such extra punches as will cut a perforated expression line and other perforated symbols as part of the original 45 single operation of perforating the roll.

Accordingly I take for my dynamic or expression line a plurality of perforations following one another successively and forming a straight line which traverses the 50 note sheet throughout the perforated portion thereof and parallel to the sides thereof. I use for such line circular perforations of a larger size than the perforations which occur in the body of the note sheet and 55 which operate the automatic player, in order that such line may be more readily followed, although perforations of any desired shape or size may be used. And I select as a convenient location for such line a portion of 60 the space on the right edge of the note sheet, between the perforations corresponding to the highest note of the piano scale and the edge of the paper, although any other desired location on the note sheet may 65 be used.

In deciding upon the manner in which such line so composed of a plurality of perforations shall be used and shall indicate its meaning to the performer, I fix upon the relative propinquity of the perforations in such line to one another as indicating the relative degrees of loudness or softness to be observed. That is to say, where the perforations in such line are closest together the music is to be played loudest, and where 70 such perforations are farthest apart the music is to be played softest. As the perforations come gradually closer together the music is to be played gradually louder, and as the perforations go gradually farther 75 apart the music is to be played gradually softer.

I fix upon a distance of two inches between perforations in such line as indicating the smallest dynamic degree, or pianissimo, 80 and a distance of one-eighth of an inch between perforations in such line as indicating the greatest dynamic degree, or fortissimo. Perforations one inch and a half apart will 85 indicate piano, perforations one inch apart 90 will indicate mezzo-forte, and perforations one-half inch apart will indicate forte. Further subdivisions of distance between perforations will indicate further subdivisions of dynamic degree. Any other desired 95 distances between perforations may be adopted and given any desired dynamic values.

Crescendos and diminuendos are indicated by gradually diminishing or gradually increasing distances between perforations in such line, and the crescendos and diminuendos may be made more or less gradual by a more or less gradual change in distances 100 between perforations.

For expression indications other than the dynamic line I employ square perforations, as such perforations can readily be made on the perforating machines now in use, by the employment of a square punch. As a 105 location for such expression indications I select a portion of the space on the right edge of the note sheet, between the perforations of the dynamic line and the edge of the paper. But perforations of any desired 110 shape or size may be used, and any desired 115 location on the note sheet may be chosen for the same.

As the expression indications on note sheets, other than the dynamic line, consist 120 largely of tempo indications, I use for such tempo indications three symbols made from the square perforations mentioned in the preceding paragraph—a single square perforation representing a tempo of 50 to 60 125 as commonly indicated, two square perforations in close proximity to one another representing a tempo of 70 to 80, and three square perforations in close proximity to one another representing a tempo of 90 to 130

100. But as many symbols may be used as desired, representing as many tempos as desired, or representing any desired number of expression indications or directions as 5 to the performance of the music or the operation of the sheet. And any other symbols capable of perforation may be adopted and used.

10 The drawing shows a portion of a note sheet on which appears an illustrative embodiment of my invention. An arrow indicates the assumed direction of travel of the note sheet.

15 The line of circular perforations at the right edge of the note sheet, beginning at 1, and continuing through 2, 3, 4, 5, 6, 7, 8 and 9, to 10, constitutes the dynamic or expression line.

20 The square perforations, Q, R R and S S S, at the right edge of the note sheet, form symbols constituting the tempo indications.

25 The transverse lines, m , m' , m^2 , m^3 , m^4 , m^5 , m^6 , m^7 , m^8 , and m^9 , divide the note sheet into nine sections, according as the music represented by the note sheet is assumed for the purpose of illustration to demand varying dynamic treatment for each section.

30 For example, it is assumed for the purpose of illustration that the music cut into the note sheet represented in the drawing as between the lines m , m' , demands that it be played fortissimo, or very loud. Accordingly the dynamic line indicates fortissimo for the section m , m' ; that is to say the dynamic line begins at 1 to be made up of perforations $\frac{1}{8}$ of an inch apart on full scale, the degree of propinquity fixed as indicating the greatest dynamic degree, and 40 it so continues throughout the section m , m' , until the music demands a different dynamic degree, at 2.

45 It is assumed that the music begins at the line m' to demand that it be played forte, or loud. Accordingly the dynamic line begins at 2 to be made up of perforations $\frac{1}{4}$ of an inch apart on full scale, the degree of propinquity fixed as indicating forte, and it so continues throughout the 50 section m' , m^2 , to 3.

55 The music within the section m^2 , m^3 , is assumed to demand that it be played mezzo-forte, or moderately loud, and accordingly the dynamic line from 3 to 4 is made up of perforations one inch apart on full scale, the degree of propinquity fixed as indicating mezzo-forte.

60 The music within the section m^3 , m^4 , is assumed to demand that it be played piano, or soft, and accordingly the dynamic line from 4 to 5 is made up of perforations one and $\frac{1}{2}$ inches apart on full scale, the degree of propinquity fixed as indicating piano.

65 The music within the section m^4 , m^5 , is assumed to demand that it be played pianissimo, or very soft, and accordingly the dynamic line from 5 to 6 is made up of perforations two inches apart on full scale, the degree of propinquity fixed as indicating pianissimo.

70 The music within the section m^5 , m^6 , is assumed to demand that it begin at m^5 to make a crescendo, that is, to be played gradually louder, and so continues until it reaches fortissimo at m^6 . Accordingly the 75 dynamic line begins at 6 to diminish gradually the distance between the perforations of which it is composed, until at 7 they are $\frac{1}{8}$ of an inch apart on full scale, the degree of propinquity fixed as indicating 80 fortissimo.

85 The music within the section m^6 , m^7 , is assumed to demand that it be played fortissimo, and the dynamic line from 7 to 8 indicates fortissimo, as hereinbefore explained.

90 The music within the section m^7 , m^8 , is assumed to demand that it begin at m^7 to make a diminuendo, that is, to be played gradually softer, and so continue until it reaches pianissimo just before m^8 . Accordingly the dynamic line begins at 8 to increase gradually the distances between the perforations of which it is composed, until just before 9 they are two inches apart on full scale, the degree of propinquity fixed 95 as indicating pianissimo.

100 The music within the section m^8 , m^9 , is assumed to demand that it be played fortissimo, and the dynamic line from 9 to 10 indicates fortissimo, as hereinbefore explained.

105 It is assumed for the purpose of illustration that the music cut into the note sheet represented in the drawing as between the lines m , m^8 , demands that it be played at a tempo of 50 to 60 as shown on the familiar tempo indicator. Accordingly the single square perforation Q, placed a short distance in advance of the line m , indicates, as heretofore explained, a tempo of 50 to 60, which continues to be the indicated 110 tempo throughout the sections m^8 , m^9 .

115 The music within the sections m^6 , m^8 , is assumed to demand that it be played at a tempo of 70 to 80, and accordingly the two square perforations, R R, in close proximity to each other, and placed a short distance in advance of the line m^6 , indicate, as heretofore explained, a tempo of 70 to 80, which continues to be the indicated tempo throughout the sections m^6 , m^8 .

120 The music within the sections m^8 , m^9 , is assumed to demand that it be played at a tempo of 90 to 100, and accordingly the three square perforations, S S S, in close proximity to one another, and placed a short distance in advance of the line m^8 , indicate, as heretofore explained, a tempo of 90 to 100, which continues to be the indicated tempo throughout the section m^8 , m^9 .

125 It is to be understood that the illustrated 130

embodiment of the invention which is shown in the drawing may be variously modified to show symbols of interpretation made up of perforations of different sizes or shapes, 5 or differently located or arranged upon the note sheet, or differently combined or grouped upon such sheet, or differently interrelated, and the invention may be variously embodied otherwise, all within the 10 scope of the subjoined claims.

I claim:

1. In a perforated note sheet, a plurality of perforations which perform no automatic or mechanical function in the operation of 15 a playing machine, but are designed solely to be seen and followed by the eye, which perforations are located in some position on the note sheet not required for the production of the music, and where they may 20 be readily observed and follow one another successively, forming a straight and continuous line which traverses the note sheet parallel to the sides thereof, said continuous line constituting an expression or dynamic 25 line which indicates to the observer the dynamic conditions and changes appropriate to the music or to the operation of such sheet by means of the relative degrees and changes of degree of propinquity to 30 one another of the perforations of which such line is made up, according to an arbitrary symbolism by which a certain assumed degree of propinquity indicates a certain dynamic degree, and another assumed degree 35 of propinquity indicates another dynamic degree, and intermediate degrees and changes of degree of propinquity indicate corresponding intermediate dynamic degrees and changes of degree.
2. In a perforated note sheet, a plurality 40

of perforations which perform no automatic or mechanical function in the operation of a playing machine, but are designed solely to be seen and followed by the eye, and are located in some position on the note sheet 45 not required for the production of the music, where they may be readily observed, and which by their size and shape, and by their location and arrangement upon the note sheet, and by their combination and grouping 50 and their degree of propinquity with respect to one another upon such sheet, constitute symbols, recognizable as such by the eye, and capable of receiving, embodying 55 and representing separate and differentiated definitions, meanings, interpretations and instructions incident to the performance of the music and the operation of the sheet, and of transmitting the same to the observer. 60

3. In a perforated note sheet, a plurality of perforations which perform no automatic or mechanical function of a playing machine but are designed solely to be seen and followed by the eye, and are located 65 in some position on the note sheet not required for the production of the music where they may be readily observed, said perforations being spaced with their degree of propinquity depending upon the dynamic 70 degree with which the instrument should play the music from the note sheet.

In testimony whereof I have hereunto set my hand in the presence of two subscribing witnesses.

FREDERICK HOPKINS.
